(57) **CLAIM**

The ornamental design for a Lamp as shown and described.

DESCRIPTION

FIG. 1 is a perspective view of, a LAMP showing my new design;

FIG. 2 is a front view thereof;

FIG. 3 is a rear view thereof;

FIG. 4 is left side view thereof;

FIG. 5 is a right side view thereof;

FIG. 6 is a top view thereof; and

FIG. 7 is a bottom view thereof.

The broken lines shown in the drawings illustrate portions of the lamp and form no part of the claimed design.

1 Claim, 7 Drawing Sheets
